UNITED STATES PATENT OFFICE

DAVID TURCOTT, OF BELOIT, WISCONSIN, ASSIGNOR TO YATES-AMERICAN MACHINE COMPANY, OF BELOIT, WISCONSIN, A CORPORATION OF DELAWARE

AUTOMATIC TURNING MACHINE

Application filed November 4, 1929. Serial No. 404,595.

The present invention relates to automatic wood-turning lathes of the type in which the work is brought into engagement with rotating knives and is rotated on its own axis while in such engagement.

The principal object of the invention is to provide a novel pneumatically operated tail stock for such a lathe, which tail stock is in many respects a very distinct improvement over the tail stocks heretofore employed.

A tail stock constructed in accordance with the invention is instantaneous and dependable in its operation, grips the work firmly when actuated by the operator, and releases the work automatically after the turning operation has been completed.

Other objects and advantages of the invention will be apparent upon a full understanding of the construction, arrangement and operation of the improved tail stock.

In order that the invention may be readily understood, one form of the same is presented herein, but it will of course be appreciated that such form has been chosen merely for the purpose of exemplification and that the invention is susceptible of embodiment in other structurally modified forms coming equally within the scope of the appended claims.

In the accompanying drawings:

Fig. 1 is a front view of a lathe equipped with the improved tail stock;

Fig. 2 is a transverse section through the lathe, taken on the line 2-2 of Fig. 1;

Fig. 3 is a front view of the tail stock, showing the same in its projected or operative position;

Fig. 4 is a longitudinal horizontal section through the tail stock, taken on the line 4-4 of Fig. 3;

Fig. 5 is a transverse section, taken on the line 5-5 of Fig. 3;

Fig. 6 is another transverse section, taken on the line 6-6 of Fig. 3;

Fig. 7 is a front view of the tail stock, corresponding to Fig. 3 but showing the same in its retracted or inoperative position;

Fig. 8 is a longitudinal horizontal section

through the tail stock, taken on the line 8-8 of Fig. 7;

Fig. 9 is a transverse section, taken on the line 9-9 of Fig. 7; and

Fig. 10 is another transverse section, taken on the line 10-10 of Fig. 7.

The lathe shown in the drawings includes a main frame 10, a set of rotating knives 11 supported by the frame, a carriage 12 pivoted at 13 to the frame for movement toward and away from the latter, a head stock 14 on the carriage having a rotating chuck 15, a tail stock 16 on the carriage having a rotating chuck 17, and a hand lever 18 pivoted at 19 to the frame and connected by a link 20 to the carriage for moving the latter to bring the piece of rotating stock gripped between the chucks into engagement with the rotating knives for the period of the cutting operation.

The tail stock 16—in which the present invention is embodied—includes an elongated circular casing 21 which is provided with a flat outspread attaching base 22. The base 22 rests upon the top of the carriage adjacent the right end thereof, and is held in any desired position longitudinally of the carriage by bolts 23 which extend into and interlock with a longitudinally extending T-shaped slot 24 in the top of the carriage, which slot also serves as a guideway for a positioning rib 25 on the bottom of the base.

The chuck 17 of the tail stock is detachably secured to a long spindle 26 which extends through the casing 21 from one end to the other and is journaled in a sleeve 27 on two spaced series of roller bearings 28 and 29. The sleeve 27 is shiftable longitudinally within a close fitting cylindrical bore 30 formed in the left end of the casing, in air-tight association therewith, and terminates in an integral piston 31 which is shiftable longitudinally within a close fitting cylindrical bore 32 of greater diameter than the bore 30 formed in the center of the casing, likewise in air-tight association therewith. The chuck 17, with the spindle 26 and the sleeved piston 31, is shiftable to the right, from the projected or operative position shown in Fig. 4 to the retracted or inoperative position

shown in Fig. 8, against the yielding resistance of a strong coil spring 33 which encircles the spindle and is compressed between a collar 34 keyed to the latter and a plug 35 5 screwed into the right end of the casing. The chuck 17 is caused to shift in the direction described by an inrush of compressed air or other fluid which enters the bore 32 of the casing through an inlet port 36 and acts 10 against the left side of the piston in the annular chamber 37 formed about the portion of the sleeve 27 which projects into the bore 32. When the chuck 17 is to be shifted in the opposite direction, into engagement with 15 the end of a piece of work, the air in the chamber 37 is released through an exhaust port 38, and the spring 33 projects the chuck with sufficient force to embed it firmly in the end of the work.

20 The compressed air which is used in retracting the chuck 17 against the resistance of the spring 33 is conducted through a flexible hose 39 to a pipe 40, which pipe in turn conducts the air to a spring-seated valve 41 25 which is positioned in a housing 42 attached to the side of the casing 21 in communication with the inlet port 36. When the valve 41 is seated, as shown in Fig. 5, the air is prevented from entering the chamber 37, but, 30 when such valve is raised up off of its seat by the engagement of a tappet screw 43 in one end of a rocker 44 with an aligned stem 45 on the valve, as shown in Fig. 9, the air enters the chamber 37 and forces the piston to 35 the right, thereby retracting the chuck into its inoperative or loading position. Whenever the valve 41 is opened, another spring-pressed valve 46 in communication with the exhaust port 38 is closed, and, whenever the 40 valve 41 is closed, the valve 46 is opened, the valve 46 being actuated by a tappet screw 47 in the opposite end of the rocker 44.

The rocker 44 is pivoted at 48 to the housing 42, and, in the projected position of the 45 chuck 17, is tilted into the air-releasing position shown in Fig. 3 by a spring 49 which is compressed between the rocker and the housing. When the turning operation on the piece of work has been completed, the operator 50 swings the carriage 12 back away from the frame 10 by moving the hand lever 18, and, when the carriage reaches a certain point in its backward travel, a cam 50 which is pivoted at 51 to a bracket 52 attached to 55 the front portion of the frame, engages with a roller 53 on one end of the rocker 44, causing the rocker to tilt from the position shown in Fig. 3 to the position shown in Fig. 7, in which latter position the inlet valve 41 is 60 opened, the outlet valve 46 is closed, and the end of the rocker opposite the roller catches under a shoulder 54 on a finger 55. The finger 55 is pivoted at 56 to the casing 21 and is connected at its free end with a 65 remote-control pull wire 57 leading through a

flexible guide tube 58 to a movable finger piece 59 on the upper end of the hand lever 18. After the piece stock to be cut has been placed in alignment with the chucks 15 and 17, either by hand, or by a loading mechanism such as that which for instance is disclosed in my co-pending application Serial No. 404,596, filed November 4, 1929, the operator trips the finger 55 from the rocker 44 by moving the finger piece 59, and the chuck 17 is in consequence forced into the end of the work, in readiness for the operator to swing the carriage 12 toward the frame 10 to commence the cutting operation. As the carriage 12 moves forwardly, the roller 53 on the rocker 44 moves into engagement with the back of the cam 50, and the cam, being free to turn in a counterclockwise direction as viewed in Fig. 2, rides out of the path of the roller without affecting the latter. The finger 55, instead of being tripped with the finger piece 59 on the hand lever, may be tripped if desired by moving a handle 60 which projects forwardly from the lower end of the finger. 90

The chuck 17 is rotated by a gear 61 which is splined onto the collar 34 at 62, which arrangement permits the collar to shift axially within the gear when the chuck 17 and spindle 26 are shifted axially. The gear 61 receives its rotary movement from a pinion (not shown) which is splined onto a driving shaft 63. The chuck 15 of the head stock 14 is similarly rotated from the shaft 63. 100

I claim:

1. In a lathe, a frame, a plurality of knives mounted for rotary movement on the frame, a carriage hinged for movement toward and away from the frame from a loading position to a cutting position and back again, manually operated means for moving the carriage, head and tail stocks having axially aligned work-engaging members for holding a piece of work therebetween, spring means for shifting one of the work-engaging members toward the other to grip the work, fluid-operated means for shifting the same work-engaging member away from the other to release the work, means for automatically actuating the fluid-operated means when the carriage is moved away from the frame upon completion of the cutting operation, and manually operated means for rendering the fluid-operated means inoperative whereby to allow the spring means to operate. 110

2. In a lathe, a frame, a plurality of knives mounted for rotary movement on the frame, a carriage hinged for movement toward and away from the frame from a loading position to a cutting position and back again, a hand lever for moving the carriage, head and tail stocks having axially aligned work-engaging members for holding a piece of work therebetween, spring means for moving one of the work-engaging members toward the other to 120

125

130

grip the work, fluid-operated means for shifting the same work-engaging member away from the other to release the work, means for automatically actuating the fluid-operated means when the carriage is moved away from the frame upon completion of the cutting operation, and a trigger device on the hand lever for rendering the fluid-operated means inoperative whereby to allow the spring means to operate.

In witness whereof I have hereunto subscribed my name.

DAVID TURCOTT.
